**FUEL FEED AND POWER CONTROL DEVICE
FOR COMBUSTION ENGINES**

Lester L. Robinson, Anderson, Ind., assignor to Bendix Aviation Corporation, South Bend, Ind., a corporation of Delaware

Application February 1, 1955, Serial No. 485,533

10 Claims. (Cl. 60—39.24)

This invention relates to a fuel feeding device for combustion engines and more particularly to speed governing mechanism therefor; it has been found to be most particularly adapted for use with combustion engines of the gas turbine type.

It is common practice to utilize centrifugal governing mechanism of the mechanical fly-weight type to control a fuel metering or throttle valve in fuel control systems for gas turbine engines, the governing mechanism including a governor spring which is normally manually adjustable by the pilot to accelerate and decelerate the engine to a selected speed.

The most widely used type of governing mechanism for gas turbine engines has been the so-called proportional type, wherein any deviation in engine speed from an equilibrium setting or operating condition results in a fuel flow correcting opening, or closing, movement of the throttle valve which is proportional to the speed deviation. One of the primary advantages of this type of governor as compared, for example, with an isochronous or non-speed deviating type, relates to the fact that the above noted proportional action results in engine operating stability, since the valve does not travel to a fully open or fully closed position whenever a slight deviation in engine speed occurs, with subsequent hunting for an equilibrium location.

Heretofore, proportional type governors for gas turbine engines have been classifiable in two main groups, viz. the direct acting kind in which the fly weights and governor spring act directly on the throttle valve, and the servo actuated type in which the governing mechanism functions through a power boost travel type servo device to control the position of the valve. The former type is well illustrated in the Mock Patent No. 2,689,606, filed December 13, 1946, and the latter type in the copending application of Andrew A. Kuzmitz, Serial No. 446,335, filed July 28, 1954 (common assignee) now abandoned.

One of the disadvantages of both of the above mentioned classes of proportional type governors is that maximum throttle valve travel is limited by the amount of displacement which can be imparted thereto by the movement of the centrifugal weights, either directly, as in the Mock patent, supra, or through servo mechanism, as in the Kuzmitz application, supra. In a copending application of Harry C. Zeisloft, Serial No. 485,226, filed January 31, 1955 (common assignee), this disadvantage is overcome by the provision of a servo powered proportional type governor in which the position of the throttle valve is almost wholly independent of centrifugal weight position. This has been accomplished by utilizing what may be termed a force type servo governor mechanism in which centrifugal weight force alone is converted into valve travel, as distinguished from a travel type servo governor mechanism in which centrifugal weight travel, resulting from a change in force output, is converted into valve travel. The governor mechanism which is disclosed and claimed in the above mentioned Zeisloft application

2

is also disclosed herein in combination with other mechanism invented by me.

My invention provides a throttle valve reset mechanism in combination with the above mentioned governing mechanism and operative on demand by the pilot or operator to increase fuel flow to the engine at a given governor setting, as is required to maintain the selected speed during, for example, a period when a secondary liquid, such as alcohol or water, is being injected into the inlet section of the compressor for increasing the mass of fluid flowing to the engine burners, and thereby the velocity and net thrust of the jet stream at the exhaust nozzle of the tailpipe. The injection of water or alcohol at the inlet of the compressor of a gas turbine engine effects a substantial increase in jet thrust if engine speed is maintained constant during such injection. It has been found most desirable to provide for the injection of such a liquid at the compressor during take-off operation of the aircraft. My invention allows secondary liquid injection to be used without any change in engine speed, and with a substantial increase in thrust output.

This invention is illustrated in Figures 1 and 2 of the drawings in a fuel control device of the so-called three-dimensional cam type, which type of control is fully disclosed in another copending application of Harry C. Zeisloft, Serial No. 248,402, filed September 26, 1951 (common assignee) now abandoned.

One of the primary objects of this invention is to provide means associated with an engine speed governor for effectively resetting the governor to maintain a prior selected speed during augmented thrust operation of the engine or to obtain any speed which may be more compatible with thrust augmentation.

Another object of this invention is to provide reset mechanism in combination with an engine speed governor and means for conducting liquid to the inlet of a compressor of a gas turbine engine.

Another object of this invention is to provide means for coordinating the operation of an engine speed governor with means for conducting liquid to the compressor or burner section of a gas turbine engine.

A further object of this invention is to provide a governor for combustion engines having mechanism for shifting the fuel cut-off characteristic of the governor in a predetermined manner following initiation of a change in operational characteristics of the engine.

Still another object of this invention is to provide a first means for controlling a first fluid to the burner of a gas turbine engine, a second means for controlling a second fluid to the compressor of such an engine, and a third means for varying the control of the first means following initiation of control by the second means.

Additional objects and advantages of this invention will become apparent to those skilled in the art in view of the following description taken in conjunction with the drawings, wherein;

Figure 1 is a sectional schematic view of a gas turbine engine and a diagrammatically illustrated fuel control system connected thereto;

Figure 2 is a sectional schematic view of an engine governor, and associated mechanism adapted to be used in the fuel control device of Figure 1, in accordance with the invention; and

Figure 3 is a curve chart, illustrating the operational characteristics of the mechanism shown in Figure 2 when installed in a control system of the type shown in Figure 1.

Figure 4 is a partial schematic showing of the compressor discharge pressure responsive rack member operative with the gear sector extending from the fuel metering valve member as shown in Figure 1.

Figure 5 is a schematic showing of a modification of the apparatus shown in Figure 1.

Referring now to Figure 1, a gas turbine engine is generally indicated at 10 and includes a series of angularly disposed combustion chambers 11 mounted in a casing having a header or air intake section 12, and a compressor 13, shown as of the axial flow type, which is driven by means of a turbine 14 through a shaft 15. Each of the combustion chambers is provided with a burner nozzle 16 to which metered fuel is supplied under pressure by way of a conduit 17, fuel manifold 18 and individual fuel lines 19. The conduit 17 receives metered fuel from a fuel control device, generally indicated at 20 in Figure 1, which includes the applicant's governing mechanism as shown in Figure 2. A pump 22 supplies fuel under pressure to fuel control 20 through a conduit 24, a portion of which fuel may be by-passed back to the pump inlet through a conduit 26.

The fuel control 20 contains mechanism adapted to respond to compressor inlet temperature (T_a), as sensed by a temperature bulb 28, compressor inlet pressure (P_a), picked up by a pitot tube 30, compressor discharge pressure (P_c), picked up at a second pitot tube 32, engine speed (N), which is transmitted to said control by means of a bevel gearing arrangement 34 and 36 and a governor drive shaft 38, and to the position of a pilot's control lever 40, which is connected to the fuel control device by means of a link 42, a lever 44 and a shaft 46.

The control lever 40 is mounted on a rotatable shaft 48 in a control quadrant 50 and is manually actuatable to select any desired operating speed for the engine by means of the link and lever 42 and 44 and other mechanism to be described, and to initiate the injection of a secondary liquid to the inlet section of the compressor 13 by means of a link, lever and shaft 52, 54 and 56, respectively, which are positionally controlled by a cam 58 mounted on shaft 48 for controlling valvular means, not shown, in a liquid flow regulator 60. An inlet conduit 62 conducts a liquid from a pump 63 to the regulator 60 whenever injection thereof is initiated, said regulator discharging the liquid to the inlet section of the compressor through a discharge conduit 64, a manifold 66, and a plurality of nozzles 68. Whenever the pilot actuates lever 40 to a full forward position, to initiate the injection of the secondary liquid, hereinafter called water, to the inlet of the compressor, a pair of bar contacts 70 and 72 close an electrical circuit through the pilot's lever 40, a lead 74, a solenoid valve 76 mounted on fuel control 20, and a ground 78, which action results in effectively resetting the governing mechanism throughout the period of time that water is injected at the compressor in a manner and for a purpose to be later described.

Referring now to Figure 2, the governing mechanism is shown contained within a housing 80 of the fuel control device 20, which receives fuel at a pressure P_1 from conduit 24 in an inlet passage 82 and an annular chamber 84 formed between the housing and a fixed cylindrical sleeve member 86, and which discharges fuel to the metering fuel conduit 17 at pressure P_2 by way of a port 88, formed in the surface of a reciprocable and rotatable hollow cylindrical metering valve member 90 and adapted to variably register with a port 92 formed in sleeve 86, a valve chamber 94, valve ports 96, sleeve ports 98, an annular chamber 100 and a fuel outlet passage 102.

The angular position of metering valve 90 is at all times controlled as a function of compressor discharge pressure by a geared rack member 104 and a gear sector 106 fixed on an extension 108 of valve 90 and having splined gear teeth 110 in mesh with the gear teeth of rack 104. The geared rack 104 is movable in a plane which is vertical to the drawing, and is positionally controlled as a function of compressor discharge pressure by mechanism such as is disclosed in the copending

application of Harry C. Zeisloft, Serial No. 248,402, supra, to which the Pitot tube 32 is connected by way of conduit 112, said rack and the sector 106 cooperating to maintain a given angular position of valve 90 for each value of compressor discharge pressure.

The axial position of metering valve 90 within sleeve 86 is controlled either by a contoured three-dimensional acceleration cam 114, which is adapted to cooperate with a cam follower and valve rod 116 and 118 during an acceleration of the engine, or by all-speed governing mechanism contained within housing chamber 120 and connected to the metering valve by a power servo piston 122 and a walking beam 124. The walking beam 124 is adapted to be variously fulcrumed at a ball joint connection 126 on a servo piston rod 128, at a pivot connection 130 to a rod 132 of a water injection governor reset piston 134, or at a ball joint connection 136 on the cam follower rod 118 in a manner to be described. The axial position of valve 90 is at all times determined by that mechanism which demands the least quantity of fuel, i. e. the acceleration cam and the governing mechanism are arranged in mutually overriding relation, as hereinafter described, so that that one which tends to fix the smallest area at metering ports 88, 92 controls.

The acceleration cam 114 is mounted on a shaft 138 which is rotatably and axially actuatable as a function of certain engine operating parameters such as, engine speed and compressor inlet temperature. The shaft 138 carries a pinion 139 fixedly secured thereto, said pinion being engaged with and rotated by a rack 141 formed on a rod fixedly secured to a piston 143. The piston 143 is responsive to a servo pressure P_s which is controlled by a half-ball servo valve 145. The half-ball servo valve 145 is positioned as a function of engine speed by a pivot lever 147 operatively connected between said half-ball servo valve and the centrifugal weights 160. The shaft 138 is positioned axially by a bellows 149 which has an operative connection with the temperature bulb 28 by means of a tube 151, the bellows and tube being filled with suitable fluid or naturally responsive to temperature changes registered by the bulb 28. The structural details and mode of operation of the above-mentioned mechanism for rotatably and axially actuating the shaft 138 is conventional and will be easily understood by those skilled in the art. The acceleration fuel flow schedule may be controlled by the cam to vary as a predetermined function of P_c , T_a and N, such that maximum allowable turbine inlet temperature is substantially maintained throughout a predetermined portion of the acceleration schedule, and the phenomenon known as compressor surge or stall is not encountered. The angular and axial position controls for valve 90 at all times cooperate to define a metering area 140 formed at the portion of registry between ports 88 and 92. For example, as compressor discharge pressure increases, rack 104 actuates gear sector 106 to move valve 90 in a clockwise direction, as viewed from the top thereof, increasing dimension x of the metering port in proportion to the increase in said pressure, and variation in any engine operating parameter which effects a change in the axial position of metering valve 90 varies dimension y of port 140.

Preferably, a constant fuel pressure differential is at all times maintained across metering port 140 by a regulator valve means generally shown at 153 and preferably of the type disclosed in U.S. Patent No. 2,689,606, granted September 21, 1954, to Frank C. Mock and assigned to the present assignee whereby the flow through said port is always a predetermined function of only those engine operating parameters which control the angular and axial positions of valve 90.

The governor mechanism contained within chamber 120 connects the pilot controlled levers 40 and 44 to the power servo piston 122 by way of the shaft 46, a governor setting cam 142 mounted on shaft 46 for rotation

therewith and adapted to be axially actuatable by compressor inlet pressure and/or temperature responsive mechanism, a cam follower rod 144, a speed selecting governor spring 146 mounted between spring retainers which abut the rod 144 and a servo valve lever 148, fulcrumed at 150, a half-ball type servo valve 152 connected to the lever 148 and cooperating with a discharge orifice 154 in a servo pressure passage 156, a governor feedback tension spring 158 resiliently connecting the servo piston rod 128 with the left end of servo lever 148, and a pair of rotatable centrifugal weights 160 mounted on brackets 162 at pivots 164 for rotation with a mounting plate 166 which is keyed to the governor drive shaft 38, said centrifugal weights having foot members 168 in abutment with a flange 170 of a force transmitting rod 172, which in turn abuts a lever 174 pivoted at 176 for transmitting a moment of the force output of weights 160 to servo lever 148 at a governor slope adjusting nut 178. The compressor inlet pressure responsive mechanism may take the form of an evacuated bellows 179 suitably mounted in a sealed chamber 181 which receives compressor inlet air pressure from pitot tube 30 via a conduit 183. A rod 185 extends from the movable end of bellows 179 into engagement with the shaft 46, such that a given axial position of the cam 142 is maintained for each value of the compressor inlet pressure P_a . The bellows 179 may be replaced by temperature sensing mechanism similar to the aforementioned temperature sensing bulb 28, tube 151 and bellows 149 in which case the shaft 46 could be actuated as a function of compressor inlet temperature T_a . The compressor inlet pressure responsive mechanism may be combined to form conventional density sensitive apparatus, not shown, such that the shaft 46 is positioned as a function of compressor inlet pressure and temperature.

The servo pressure (P_s) passage 156 connects the P_1 pressure chamber 84 to chamber 120, which is connected to pump by-pass conduit 26 by a passage, not shown, at pump inlet pressure P_o . A discharge pressure regulator valve 180 in passage 156 is adapted to maintain a constant pressure in said passage upstream of a calibrated restriction 182, the pressure P_s beneath power piston 122 therefore varying solely as a function of the area ratio between restriction 182 and orifice 154. A power return spring 184 and fuel at pump inlet pressure in a chamber 186 oppose P_s pressure and spring 158 across piston 122.

A servo balance spring 188, adjustable by means of a screw 190, is utilized to act on lever 148 at 192 for the purpose of compensating for variations in manufacturing tolerances between the designed rates of springs 146 and 158, and for insuring that said latter springs will sustain a pre-load even when the engine is at rest; this latter function insures that neither spring 146 nor 158 will ever be extended to a free height or no-load condition. If either of said springs were ever to reach a no-load condition they might become disconnected from their respective retaining means. The effective force output of the balance spring 188 on the servo system remains substantially constant, irrespective of variations in engine operating conditions, as the result of an arrangement which effects a total range of movement of servo valve 152 amounting to only a few thousandths of an inch.

During all conditions of engine governing and equilibrium operation, except during a period of water injection, the fulcrum 130 of walking beam 124 is maintained in the position shown by opposed spring loaded pistons 134 and 194, which are reciprocable within a cylinder 196, and which are urged in opposite directions by springs 198 and 200 in chambers 202 and 204, respectively. A chamber 206, formed between said pistons, is normally connected to pump inlet pressure P_o in housing chamber 120 by way of a restriction 208, a passage 210, chamber 204, and a pair of bleeds 212 in the piston 194. The chamber 202 is vented to pump inlet pressure through a

housing aperture 214. The position of piston 194 is normally fixed by an annular stop member 216.

The solenoid valve 76 comprises a valve member 218, which is normally held in a closed position in a water conducting conduit 220 by a spring 222, and a suitably wound coil 224 connected to the ground 78 and to the electrical bar contact 72 by lead 74, said coil being energizable to actuate valve 218 against spring 222 and permit water to enter a chamber 226 by way of a conduit 220, which may be connected to the conduit 62. The chamber 226 connects with the drain conduit 228 through a port 230, and is formed on one side of a diaphragm 232 to which is connected a double acting valve 234, said valve being adapted to allow connection between a P_1 fuel pressure conduit 236 and the chamber 204 during a period of water injection following a demand therefor by the pilot. A demand for water injection causes energization of solenoid valve 76 and a differential pressure across diaphragm 232 in an upward direction, which results in closing port 230, and opening conduit 236 to chamber 204. A chamber 238 formed on the upper side of diaphragm 232 is connected to chamber 120 by a passage 240. Following a demand for water injection, fuel at pressure P_1 flows from chamber 204 through piston bleeds 212 into chamber 206 to actuate piston 134 upwardly against spring 198 until the end of piston rod 132 abuts an adjustable water injection stop 242, thereby establishing a new position for the fulcrum 130.

In Figure 4 there is a schematic view of the compressor discharge pressure responsive rack 104 operative with the gear sector 106 which is formed on an extension 108 of the fuel metering valve member 90 and which has splined gear teeth 110 in mesh with the gear teeth of rack member 104. The rack 104 is formed on a rod 105 which is fixedly secured to the movable end of an evacuated bellows 107. The bellows 107 is mounted in a sealed chamber 109 which receives compressor discharge pressure P_c from Pitot tube 32 via conduit 112. The bellows 107 responds to the compressor discharge pressure P_c in chamber 109 and rotates valve 90 through rack 104 and sector 106 such that a given angular position of valve 90 is maintained for each valve of compressor discharge pressure P_c .

In Figure 5 there is a schematic showing of a modification of a portion of the apparatus shown in Figure 1. The water injection governor reset piston 134 is shown connected through the rod 132 to the walking beam 124 at a pivot connection 130. Also the ball joint connection 126 of the walking beam 124 is shown. The spring 198 within chamber 202 is shown urging the reset piston 134 in an opposite direction within the cylinder 196 relative to the piston 194 which is urged by the spring 200 within the chamber 204. The chamber 206 formed between the pistons 134 and 194 is normally connected to pump inlet pressure P_o in the housing chamber 120 by way of the restriction 208, the passage 210, the chamber 204, and the bleeds 212 in the piston 194. The angular stop member 216 normally fixed the position of the piston 194. The double acting valve member 234, described as connected between the conduit 236 and the chamber 204 and responsive to water injection, is shown.

In accordance with the modification as shown in Figure 5 a control bleed 262 is provided to vent the chamber 202 to the housing chamber 120 and a control valve including a movable valve member 264 is connected between conduit 236 containing high pressure fuel and the chamber 202 at the top side of the reset piston 134. The valve member 264 is controlled in position by a pressure drop responsive diaphragm 266, which is responsive to the pressure within the tailpipe of engine 10 behind the turbine 14 as vented to the chamber 268 and is responsive to atmospheric pressure surrounding the engine 10 as vented to the chamber 270. The control spring member 272 provides the control for determining the tailpipe pressure drop necessary before the high pressure fuel

from the conduit 236 is vented to chamber 202 and the top side of the reset piston 134.

Operation

Referring now to Figure 3, sea level acceleration, governing, and steady state engine characteristics are qualitatively illustrated by the curves 244, 246 and 248 and 250, respectively, on the curve chart which is plotted on the coordinates of fuel flow in pounds per hour versus engine speed in r.p.m. The basic contour of the characteristic sea level acceleration curve 244 is fixed by the contour of the acceleration cam 114, which is actuatable as a function of certain engine operating parameters, as hereinbefore described, whereas the height or level of said curve above the engine speed coordinate is primarily controlled by the compressor discharge pressure responsive mechanism. The governor fuel cut-off curve 246 illustrates the operation of the force servo type proportional governor from the acceleration curve to a selected speed point on an engine steady state operating curve. The steady state curve 248 illustrates engine fuel flow demand at any given engine speed during sea level operation without water injection at the compressor inlet, whereas the curve 250 illustrates such engine demand with water injection.

Assume that the engine has been started and accelerated to the steady state operating point *a* in the mid-speed range. In this condition of operation the pilot's control lever 40 will be positioned approximately midway between the ends of quadrant 50, in which position solenoid valve 76 is de-energized and the pump inlet pressure in chamber 238 maintains double acting valve 234 in the position shown so that the position of fulcrum 130 is fixed, as shown. The contour of the water regulator control cam 58 is such that no movement is imparted to link and lever 52 and 54 during actuation of lever 40 to the mid-position, and no injection occurs at nozzles 68; with lever 40 in the mid-position link and lever 42 and 44 position the governor setting cam 142 on shaft 46 so as to impose a speed selecting load on governor spring 146 through cam follower rod 144 which demands that engine operating speed existent at point *a*. In this condition of operation the half-ball servo valve 152, being maintained in fixed position by an existent force balance on lever 148, controls a servo pressure P_s in passage 156 which imposes a force on servo piston 122; this force is balanced by the opposing forces of the governor feedback spring 158, the power return spring 184, and the pump inlet pressure in chamber 186, whereby the position of walking beam 124 is fixed thereby controlling the axial position of metering valve 90 such that the area of metering port 140 controls that quantity of fuel flow to the nozzle 16 which is necessary to maintain engine speed as set at point *a*.

The forces, acting on servo lever 148 in a direction which tends to move servo valve 152 in an opening direction, i.e. in a direction which would result in an accelerating fuel flow to the engine, consist of the moment forces of governor spring 146, feedback spring 158, and the fuel pressure force on servo valve 152 at orifice 154, all acting about fulcrum 150. These moment forces are opposed and balanced by the moment force of the centrifugal weights 160, which varies as the square of engine speed, and the substantially constant moment force of the servo balance spring 188. At any given speed, the engine driven centrifugal weights 160 generate an effective force output on lever 148 which is equal to the weight force output times the ratio of the lever arm between rod 172 and fulcrum 176 to the lever arm between nut 178 and fulcrum 176. The force output of weights 160 is therefore diminished at lever 148 by the lever ratio factor, said factor being adjustable by nut 178 to adjust the governor cut-off slope, as will be hereinafter described.

Assume now that the pilot actuates control lever 40

in a counterclockwise direction to select, say, a maximum operating speed for the engine, as denoted by point *d* on curve 248, and as illustrated by the position of lever 40 in Figure 1. As the pilot rotates lever 40 to the indicated

- 5 maximum speed position, the fuel control unit reacts substantially instantaneously as follows: Governor setting cam 142 is rotated on shaft 46 to a position at which the cam rise imposes maximum compression on governor spring 146 to select that speed at which the governor 10 weight force and other forces acting on servo lever 148 will be in equilibrium, as illustrated at point *d*; servo lever 148, being no longer in balance, rotates a very slight amount in a clockwise direction to increase the area ratio between orifice 154 and restriction 182, thereby 15 instantaneously decreasing servo pressure P_s and unbalancing the forces across servo piston 122; and the force unbalance across piston 122 actuates the piston downwardly and the walking beam 124 about fulcrum 130 in a clockwise direction until cam follower 116 comes into 20 contact with acceleration cam 114, in which position the metering area 140 has increased to effect an increase in fuel flow from point *a* on curve 248 to point *b* on curve 244. The amount of compression imparted to governor spring 146 which is in excess of that necessary 25 to effect an acceleration to point *g* on curve 248 results in a continued downward movement of piston 122, following contact of cam follower 116 with acceleration cam 114, about a new fulcrum 136, as pivot 130 and piston 134 actuate piston 194 downwardly against spring 30 290 until piston 122 reaches a position in which the decreased loadings on springs 184 and 158 plus the low pressure in chamber 186 again balances the force of pressure P_s ; the loading force imposed on the acceleration cam through follower 116 is thereby held to a relatively 35 small amount, which results only from the degree of compression imparted to the light spring 200.

The increase of fuel flow from point *a* to point *b* results in an excess over that required to run the engine at the existing speed, and acceleration proceeds along 40 curve 244, as determined by the contour of cam 114 which effects an opening movement of metering valve 90 in an axial direction; at the same time compressor discharge pressure responsive rack 104 effects an opening 45 rotational movement of valve 90. The combined axial and rotational movement of valve 90 results in a fuel flow versus speed characteristic such as is illustrated by the curve segment *bc*. As acceleration of the engine proceeds from point *b*, and the rate of opening movement of valve 90 is determined by the rotating cam 114, it is apparent that the fulcrum of walking beam 124 will 50 shift from pivot 136 to pivot 126, as spring 200 actuates pistons 194 and 134 upwardly until piston 194 again abuts stop 216 and pivot 130 is returned to the position shown. Contact between follower 116 and the decreasing rise of cam 114 is thereby maintained while the engine is accelerating.

At the speed indicated at point *c*, the centrifugal weights 160 have generated a force output which is sufficient to begin to overcome the force moments of governor spring 146 and feedback spring 158, said spring 158 being, at this time, in a relatively relaxed condition. Servo valve 152 therefore moves slightly upwardly to reduce the area ratio between orifice 154 and restriction 182, thereby producing an immediate increase in pressure P_s which unbalances servo piston 122 in an upward direction, resulting in a counterclockwise rotation of walking beam 124 about fulcrum 130 and a movement of follower 116 away from acceleration cam 114 to reduce the dimension *y* of metering port 140. As piston 122 moves upwardly, feedback spring 158 elongates and produces an increasing moment of force on servo lever 148 in the same direction as that produced by governor spring 146. This action results in continued acceleration of the engine as fuel flow decreases along the governor 65 break curve 246, inasmuch as the increasing force out-

put of spring 158 necessitates a proportional increase in engine speed, so that the effective force output of weights 160 plus the substantially constant force output of balance spring 188 may balance the effective force outputs of spring 146 and 158 at equilibrium operation. In other words, neglecting the substantially constant forces of springs 146 and 188, and also the small hydraulic force acting on valve 152, the increasing load on feedback spring 158 feeds into the governor mechanism a demand increase in engine speed which is proportional to the decrease in fuel flow along the governor break curve 246. This proportional governing characteristic imparts a negative slope to the fuel cut-off curve which is a function of the rate of the feedback spring, and permits the engine to reach a stable equilibrium point of operation. An unstable condition which is generally known as hunting in the governor art, would result if the feedback spring were not included in the governor mechanism; i.e. without spring 158 a substantially vertical or isochronous governing characteristic, as illustrated by dotted curve *hdi*, would result due to the relatively constant force output of governor spring 146 at any given selected speed. Again, without spring 158 a slight variation in engine speed above or below that selected by the pilot would result in movement of servo valve 152 to cause potentially maximum movement of servo piston 122 and metering valve 90 in seeking a condition of equilibrium.

When the fuel flow required to run the engine is being metered at point *d*, no accelerating engine torque exists, and the governing mechanism is in a state of equilibrium; i.e. the moments of forces acting on lever 148 in a clockwise direction exactly balances the opposing counterclockwise moments, and the positions of servo piston 122 and metering valve 90 are fixed. If, for any reason, the engine should tend to increase or decrease speed from point *d*, as with a decrease or increase in the density of the surrounding atmosphere, respectively, fuel flow would tend to vary along curve 246 to reestablish equilibrium on the new engine operating curve.

With any given fixed design rate of spring 158, the slope of the governor break curve may be manually adjusted as desired by nut 178, inward adjustment on lever 174 effecting an increase in the slope of the governor cut-off curve as a result of the increased effective force output of weights 160 with a given increase in engine r.p.m., and outward movement of nut 178 on lever 174 effecting a decreased slope of said curve.

The relative arrangement of parts, as shown in Figures 1 and 2, approximates that which would exist if an engine were being controlled by my device to operate at point *d*. It should be remembered that the fulcrum 130 of the walking beam 124 maintains a fixed position, as shown, throughout governor cut-off and equilibrium operation at any selected speed, the fulcrum of beam 124 shifting to pivot 136 only during downward motion of piston 194 against spring 209 following initial contact of cam follower 116 with the acceleration cam, and that said fulcrum shifts from pivot 136 to pivot 126 only during upward movement of piston 194 to the position indicated during an acceleration of the engine to the beginning of governor cut-off action.

A deceleration of the engine is effected by relaxing the loading of spring 146 by counterclockwise movement of pilot's lever 40, which unbalances the forces acting on lever 148 and effects an upward movement of piston 122 until piston rod 128 contacts a deceleration stop 252; as beam 124 rotates about fulcrum 130 in a counterclockwise direction to the position determined by stop 252, the axial position of metering valve 90 and the y dimension of metering area 140 are fixed. Fuel flow immediately decreases along the curve *di*, and the engine then begins to decelerate along the curve *ij* as metering area dimension *x* decreases with decreasing compressor discharge pressure. At point *j* the force output of weights 160 has decreased to such an extent that spring 146

begins to overcome said weight force output and move servo valve 152 slightly open to cause an opening movement of the metering valve 90, which increases fuel flow as the engine speed decreases along the proportional governor break curve *ja*. At point *a* the control again reaches a condition of equilibrium.

Again assume that the engine is operating at the maximum speed point *d*, and that the pilot desires to augment the thrust output thereof by providing for the injection of water at the inlet of the compressor. To initiate the injection of water the pilot rotates control lever 40 beyond the maximum speed point until the rise of cam 58 effects an opening movement of valvular means in the water regulator 60 and allows water to be injected through nozzle 68, thereby increasing the density of the air flowing to the compressor by lowering the temperature thereof and increasing the mass of the motive fluid flowing to the engine burners 11. The resultant increase in mass and density of the motive fluid establishes a new steady state operating curve, such as shown at 250, for the engine. Without the governor reset mechanism, to be hereinafter described in operation, a decrease in engine speed and an increase in fuel flow would be effected as a result of the response of my governor mechanism to the underfueling condition existent at point *d* with respect to the new steady state curve 250; i.e. the feedback spring and governor weight combination would effect downward movement of piston 122 to increase fuel flow along the governor break curve 246 to a new condition of steady state operation at point *f*. Such operation would result in an underspeed condition at point *f* with respect to the speed selected by the pilot at point *d*. In order to maintain said selected speed constant with water injection, and to realize maximum thrust augmentation from said injection, the governor reset mechanism has been provided to operate as follows: The water injecting position of control lever 40, in addition to effecting operation of regulator 60, closes the electrical bar contacts 70 and 72 to energize solenoid valve 76 in an opening direction, which allows water under pressure to enter chamber 226; upward actuation of double acting valve 234 results, thereby causing a closing of drain port 230 and connecting chamber 206 to unmetered fuel pressure *P*₁ by way of conduit 236, chamber 204, and piston bleeds 212; and the resultant increase in chamber 206 pressure actuates piston rod 132 upwardly against the adjustable water injection stop 242, thereby rotating walking beam 124 about pivot 126 to further open metering valve 90 and effect an increase in fuel flow to the engine burners. This increase in fuel flow, which is simultaneous with the injection of water, is initially calibrated by the position of injection stop 242 such that the increment increase in fuel flow is just sufficient to maintain the selected speed and the engine then operates at point *e* on the new steady state curve 250. The new position of fulcrum 130 results in the establishment of a new governor break curve 256 at maximum speed. It should be noted that governor equilibrium is not upset as fuel flow increases from point *d* to point *e* with water injection, as would be the case if the reset mechanism were not provided.

When the pilot wishes to return to a condition of normal maximum thrust operation without water injection, he simply rotates control lever 40 clockwise to the position shown, which simultaneously de-energizes water regulator 60, and solenoid valve 76, thereby returning double acting valve 234 and fulcrum 130 to the positions shown. This action effects a decrease in fuel flow from point *e* to point *d* at constant speed.

The governor reset mechanism is readily adapted for use as a protective device for an engine having afterburner thrust augmenting means, being made operative in the event of a flame-out at the afterburner nozzles to maintain engine speed at a safe value during a period when the tailgate remains open for afterburner operation. Referring to Figure 5, this operation is accomplished by

the diaphragm 266 and valve member 264 which in response to a predetermined pressure drop are biased upward whereupon the valve member 264 prevents the flow of high pressure fuel from conduit 236 to chamber 202. If afterburner flame-out should occur, the pressure in chamber 202 would drop and allow the spring 272 to bias the diaphragm 266 and valve member 264 downward whereupon high pressure fuel would be allowed to flow from conduit 236 to chamber 202. The piston 134 would move downwardly against stop 216 in response to the pressurization of chamber 202 and effect counterclockwise movement of walking beam 124 about the pivot 126 which, in turn, causes movement of metering valve 90 in a closing direction and a corresponding decrease in engine fuel flow. The controlled reduction in fuel flow effectively maintains engine speed at a safe value until the tailgate can be closed and tailpipe pressure again increased, at which time the diaphragm 266 would actuate valve member 264 to a closed position to thereby disestablish communication between conduit 236 and chamber 202. The piston 134, fulcrum 130, and metering valve 90 would then return to the positions shown to maintain the selected speed.

It will be apparent to those skilled in the art that various changes in the structure and relative arrangement of parts may be made without departing from the scope of my invention.

I claim:

1. In a fuel feed and power control system for a gas turbine engine having a burner and a compressor, a fuel conduit for conducting fuel to the burner, valve means for controlling the fuel flow through said conduit, engine speed responsive means operatively connected to said valve means for controlling the flow of fuel therethrough as an inverse function of engine speed, said operative connection including lever means having a fulcrum maintained in a normally fixed position during equilibrium operation of the engine, means for conducting an engine thrust augmenting fluid to the compressor, and means operatively connected to said fulcrum for varying the position thereof whenever injection of said fluid is initiated.

2. In a fuel feed and power control system for a gas turbine engine having a burner and a compressor, a fuel conduit for conducting fuel to the burner, first control means for conducting a thrust augmenting fluid to the compressor, second control means for initiating the flow of said fluid to the compressor, engine speed governor means for controlling the flow of fuel through said conduit, and third control means operatively connected to said governor means and responsive to the conduction of fluid to the compressor by said first control means for shifting the governor fuel cut-off characteristic following a demand for the injection of said fluid to the compressor.

3. In a fuel feed and power control system for a gas turbine engine having a burner and a compressor, a fuel conduit for conducting fuel to the burner, means for conducting an engine thrust augmenting fluid to the compressor, governor valve means for controlling the flow of fuel through said conduit, engine speed responsive means operatively connected to said valve means for controlling the flow regulating position thereof at a selected speed of engine operation, said operative connection including lever means and a fulcrum for said lever means movable from a first to a second operating position whenever said thrust augmenting fluid is conducted to the compressor, and fluid pressure responsive means adapted to actuate said fulcrum from said first to said second operating positions for maintaining the selected engine speed during injection of said thrust augmenting fluid.

4. An engine speed governor comprising governor valve means for controlling the flow of motive fluid to the engine, an engine speed responsive governor mechanism operatively connected to said valve means for controlling the flow regulating position of said valve means as an inverse function of engine speed to operate said engine

in accordance with a first steady state operating characteristic, first control means operatively connected to said engine for shifting the engine operation to a second steady state operating characteristic, second control means operatively connected to said governor mechanism for selecting an operating speed for the engine, with said latter operative connection including third control means for effectively resetting said governor mechanism to maintain the selected speed following a shift from the first to the second steady state operating characteristic of the engine.

5. An engine speed governor comprising governor valve means for controlling the flow of motive fluid to the engine, an engine speed responsive governor mechanism operatively connected to said valve means for controlling the flow regulating position of said valve means as an inverse function of engine speed to operate said engine in accordance with a first steady state operating characteristic, first control means operatively connected to said engine for shifting the engine operation to a second steady state operating characteristic, second control means operatively connected to said governor mechanism for selecting an operating speed for the engine including a fluid pressure responsive valvular means for effectively resetting said governor mechanism to maintain the selected speed following a shift from the first to the second steady state operating characteristic of the engine, and third control means responsive to actuation of said valvular means for varying the flow regulating position of said valve means at the preselected engine speed.

6. An engine speed governor comprising valve means for controlling the flow of motive fluid to the engine, an engine speed responsive mechanism operatively connected to said valve means for governing fuel flow to maintain any given selected engine speed, and control means connected to said speed responsive mechanism for selecting an operating speed for the engine, said operative connection including a walking beam, a first pivot means connecting said valve means to said beam, a second pivot means connecting fluid pressure responsive means to said beam and a third pivot means connecting said engine speed responsive means to said beam, said second pivot means having a first operating position and a second operating position, with said second pivot means being in said first position during control of said valve means by said engine speed responsive means, and with said fluid pressure responsive means being operative to actuate said second pivot to said second position in response to said speed selecting control means being moved to a predetermined control position.

7. In a fuel feed and power control system for a gas turbine engine having a burner and a compressor, a fuel conduit for conducting fuel to the burner, means for conducting an engine thrust augmenting fluid to the compressor, valve means for controlling the flow of fuel through said conduit, engine speed responsive mechanism for controlling the flow regulating position of said valve means as an inverse function of engine speed, means connected to said speed responsive mechanism for selecting an operating speed for the engine, an operative connection between said speed responsive means and said valve means including means adapted to actuate said valve means in an opening direction at a given selected engine speed during injection of said thrust augmenting fluid, and means for coordinating the actuation of said valve means by said latter means with said thrust augmenting fluid conducting means.

8. In a fuel feed and power control system for a gas turbine engine having a burner and a compressor, a fuel conduit for conducting fuel to the burner, means for conducting engine thrust augmenting fluid to the compressor, valve means for regulating the flow of fuel through said conduit, engine speed responsive mechanism operatively connected to said valve means for varying the flow regulating position thereof as an inverse function of engine speed, and means connected to said engine speed re-

sponsive means for selecting an operating speed for the engine, said operative connection including a lever, a lever fulcrum maintained in a normally fixed first position during control of said valve means by said engine speed responsive means, means permitting actuation of said fulcrum to a second position following initiation of an acceleration of the engine by said speed selecting means and means for actuating said fulcrum to a third position following initiation of flow of said thrust augmenting fluid at a given selected speed of engine operation.

9. In a fuel feed and power control system for a gas turbine engine having a burner and a compressor, a fuel conduit for conducting fuel to the burner, first control means for conducting an engine thrust augmenting fluid to the compressor, valve means for regulating the flow of fuel through said conduit, an engine speed governor mechanism operatively connected to said valve means for controlling the flow regulating position thereof, second control means connected to said governor means for selecting any given desired operating speed for the engine, said operative connection between said governor mechanism and said valve means including a control member having a first pivot connection with said valve means, means operatively connected to said control member and said second control means including a second pivot connection, means operatively connected to said control member and said first control means including a

third pivot connection, said control member being pivotally controlled about said third pivot connection during governor cut-off and equilibrium operation of the engine at any selected speed, said control member being pivotally controlled about said first pivot connection subsequent to a request for an acceleration of said engine by said second control means, and said control member being pivotally controlled about said second pivot connection subsequent to initiating a flow of said thrust augmenting fluid.

10. In a fuel feed and power control system for a gas turbine engine having a burner and a compressor, first control means for controlling the flow of a first fluid to the burner, second control means for controlling the flow of a second fluid to the compressor, and third control means operatively connected to said first means and to said second means for varying the flow of said first fluid following initiation of the flow of said second fluid by said second control means.
